[57] CLAIM

The ornamental design for a cable stripping tool, as shown.

DESCRIPTION

FIG. 1 is a left side elevational view of a cable stripping tool showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a bottom plan view thereof;

FIG. 7 is a left side elevational view thereof, with the stripping knife cassette removed for clarity of illustration;

FIG. 8 is a top plan view of FIG. 7;

FIG. 9 is a right side elevational view of FIG. 7; and,

FIG. 10 is a perspective view thereof.
